Primary Examiner — Cathron Brooks*Assistant Examiner* — Christian P McLean(74) *Attorney, Agent, or Firm* — Banner & Witcoff, Ltd.**CLAIM**

The ornamental design for a display screen with animated graphical user interface, as shown and described.

DESCRIPTION

FIG. 1 is the first image in a sequence for a display screen with animated graphical user interface showing our new design;

FIG. 2 is the second image thereof;

FIG. 3 is the third image thereof;

FIG. 4 is the fourth image thereof;

FIG. 5 is the fifth image thereof; and,

FIG. 6 is the sixth image thereof.

The outermost broken lines illustrate the display screen, and the remaining broken lines illustrate portions of the graphical user interface. None of the broken lines form part of the claimed design.

1 Claim, 6 Drawing Sheets(56)
